[57] CLAIM

The ornamental design for fluid transport tank, substantially as shown and described.

DESCRIPTION

FIG. 1 is a side elevation view of a fluid transport tank incorporating my new design.

FIG. 2 is a top plan view thereof.

FIG. 3 is a bottom plan view thereof.

FIG. 4 is a front end elevation view thereof.

FIG. 5 is a rear end elevation view thereof.

FIG. 6 is a sectional view thereof taken along line 6—6 of FIG. 1.
